DESIGN FOR A SUPPORT FOR AN INDUCTIVELY EXCITED GASEOUS CONDUCTOR TUBE

Leo L. Beck, Morristown, N. J., and William R. Price, New York, N. Y., assignors to Lustron Lights, Inc., New York, N. Y., a corporation of New York

Application October 29, 1938, Serial No. 80,764

Term of patent 14 years

To all whom it may concern:

Be it known that we, Leo L. Beck, a citizen of the United States and resident of Morristown, in the county of Morris and State of New Jersey, and William R. Price, a citizen of the United States and resident of New York city, in the county and State of New York, have invented a new, original, and ornamental Design for a Support for an Inductively Excited Gaseous Conductor Tube, of which the following is a specification, reference being had to the accompanying drawing, forming a part thereof.

Figure 1 is a perspective view of a support for an inductively excited gaseous conductor tube, showing our new design; and

We claim:

The ornamental design for a support for an inductively excited gaseous conductor tube, as shown.
